NIELS HANSEN, OF WILKINSBURG, PENNSYLVANIA, ASSIGNOR TO WESTINGHOUSE ELECTRIC & MANUFACTURING COMPANY, A CORPORATION OF PENNSYLVANIA.

CENTRIFUGALLY-ACTUATED SHORT-CIRCUITING DEVICE

Application filed June 25, 1919. Serial No. 306,624.

To all whom it may concern:

Be it known that I, NIELS HANSEN, a subject of the King of Denmark, and a resident of Wilkinsburg, in the county of Allegheny 5 and State of Pennsylvania, have invented a new and useful Improvement in Centrifugally-Actuated Short-Circuiting Devices, of which the following is a specification.

10 My invention relates to centrifugally-actuated short-circuiting devices for dynamo-electric machines, and it has particular relation to single-phase motors of the commutator type that are adapted for repulsion operation during the starting period 15 and for induction operation after a predetermined speed has been attained.

The object of my invention is to provide a simple and effective device for short-circuiting the commutator of such a motor, such device being automatically controlled 20 by a means which is responsive to variations in the speed of the motor.

Short-circuiting devices of the above-25 mentioned type, as heretofore constructed, have comprised a sleeve slidably mounted on the motor shaft and adapted to be moved longitudinally of the shaft by centrifugally-actuated levers, and, in other devices, a 30 sleeve mounted on the shaft and adapted to be moved rotatably as well as axially when being brought into engagement with the commutator cylinder. In both cases, of course, the short-circuiting device is returned to its inoperative position, by means 35 of spring members, when the motor is operating below a predetermined speed.

By my invention, I propose an improvement upon the latter structure which consists of a simplification of the actuating 40 device for such structure.

Specifically, my invention is an improvement upon the structure disclosed in application Serial No. 95,028, filed by George H. 45 Garcelon and Joseph L. Chantemerle, on May 3, 1916, and assigned to the Westinghouse Electric & Manufacturing Company.

In the accompanying drawing, Figure 1 is an end elevational view of a dynamo-electric machine constructed in accordance with 50 my invention, parts being broken away for the sake of clearness; Fig. 2 is a side elevational view of the structure shown in Fig. 1; Fig. 3 is a detail view of a casting employed in the structure shown in the other

two figures; and Figs. 4 and 5 are detail views of the weight and connecting-link members respectively employed in my device.

Referring to the drawing in detail, I show 60 a shaft 6 upon which is mounted a commutator cylinder 7 constituting a portion of a dynamo-electric machine. A short-circuiting disk 8 is slidably mounted upon the shaft adjacent to the end of the commutator cylinder 7 and is in operative engagement with a centrifugally-actuated device 9. The centrifugally-actuated device 9 consists of a supporting member 10 rigidly mounted upon the shaft and two diametrically opposite 70 centrifugal weights 11 that are pivotally mounted upon the supporting member 10 by means of pins 11a. The weights 11 are each provided with a projection 12 to which is attached a spring 13, the other end of which 75 is attached to a portion of the supporting member 10 in such manner as to oppose the centrifugal force exerted by the weight members 11. Upon two projections 14 of the supporting member 10 are pivotally mounted, by means of pins 14a, two link members 15 of substantially triangular shape which are pivotally connected to a plate 16 by means of lugs 17 thereof and pins 18.

The short-circuiting disk 8 is mounted 80 upon the plate 16 so that, when the connecting link 15 moves the plate 16 toward the commutator cylinder, the disk 8 is brought into engagement with the end of the commutator cylinder. The projections 12 on the 90 weight members 11 are each provided with a pin 19, which, when in its operative position, is disposed within a slot 20 in the connecting link 15 so that, when the weight members 11 move about their pivotal point 95 11a, the pin 19 so engages the sides of the slot 20 as to cause the link 15 to move the plate 16 and the disk 8 toward the commutator cylinder.

The pivotal point 14a, about which the 100 link 15 moves, is normally disposed at a greater distance from the commutator cylinder than is the pin 18. The object of this arrangement is to produce a rotary, as well as an axial, movement of the disk 8 when it 105 engages the end of the commutator cylinder. If the pin 18 were an equal distance from the commutator cylinder with the pin 14a, the movement of the disk would be entirely axial. This combined rotary and axial mo- 110

tion is desirable since it causes the disk to make very good contact with the commutator cylinder.

While I have described but one form of my invention and have described in detail but one application of the same, it will be obvious to those skilled in the art that it is not so limited but that various minor changes and modifications may be made therein without departing from the spirit of my invention, and I desire, therefore, that only such limitations shall be imposed thereon as are set forth in the accompanying claims.

15 I claim as my invention:

1. In a dynamo-electric machine, the combination with an armature and a commutator cylinder mounted upon a rotatable shaft, of a short-circuiting device for said commutator cylinder comprising a movable contact plate, a support mounted on said shaft, means for moving said plate into contact with said cylinder, said means comprising a single member pivotally mounted on said support and pivotally connected to said plate, and speed-responsive means for actuating said member.

2. In a dynamo-electric machine, the combination with an armature and a commutator cylinder mounted upon a rotatable shaft, of a short-circuiting device for said commutator cylinder comprising a movable contact plate, and means for moving said plate into contact with said cylinder, said means comprising a support mounted upon said shaft, a plurality of centrifugally-actuated arms pivotally mounted thereon, and link members each pivotally mounted on said support and pivotally connected to said plate, each of said links being actuated by one of said arms.

3. In a dynamo-electric machine, the combination with an armature and a commutator cylinder mounted upon a rotatable shaft, of a short-circuiting device for said commutator cylinder comprising a movable contact plate, and means for moving said plate into contact with said cylinder, said means comprising a support mounted upon said shaft, a plurality of centrifugally-actuated arms pivotally mounted thereon and pro-

vided with pins, and link members provided with a slot and pivotally mounted on said support and pivotally connected to said plate, said pins on said arms being disposed within said slot to move said links when said arms move.

4. In a dynamo-electric machine, the combination with an armature and a commutator cylinder mounted upon a rotatable shaft, of a short-circuiting device for said commutator cylinder comprising a movable contact plate, and means for moving said plate into contact with said cylinder, said means comprising a support mounted upon said shaft, a plurality of centrifugally-actuated arms provided with pins and pivotally mounted on said support, and a plurality of link members of substantially triangular shape each pivotally mounted on said support about a pin in one corner thereof, pivotally connected to said plate by a pin in a second corner thereof, and provided with a slot in the third corner with which said pins in said centrifugally-actuated arms contact to move said link members.

5. In a dynamo-electric machine, the combination with an armature and a commutator cylinder mounted upon a rotatable shaft, of a short-circuiting device for said commutator cylinder comprising a movable contact plate, and means for moving said plate into contact with said cylinder, said means comprising a support mounted upon said shaft, a plurality of centrifugally-actuated arms provided with pins and pivotally mounted on said support, and a plurality of link members of substantially triangular shape each pivotally mounted on said support about a pin in one corner thereof, pivotally connected to said plate by a pin in a second corner thereof, and provided with a slot in the third corner with which said pins in said centrifugally-actuated arms contact to move said link members, said second-mentioned pivotal pin being normally disposed closer to said commutator cylinder than said first-mentioned pivotal pin.

In testimony whereof, I have hereunto subscribed my name this 14th day of June, 1919.

NIELS HANSEN.
